DESK OF PACKING-CASE CONSTRUCTION

Edwin R. Goldfield and Ralph C. Schiring, University Heights, Ohio, assignors to Picker X-Ray Corporation Waite Manufacturing Division, Inc., Cleveland, Ohio, a corporation of Ohio

Application March 8, 1947, Serial No. 733,358

5 Claims. (Cl. 45—69)

1

This invention relates to improvements in a desk formed of packing cases.

An object of the present invention is to utilize a plurality of packing cases in which portable equipment is carried about for the purpose of providing a desk when the equipment is set up for use.

Another object of the present invention is to utilize sloping skid rails on a packing case having as one purpose to insure that the case is not set upon the floor with the skid equipped end down, and having as a second purpose to provide a support for a desk surface.

Another object of the present invention is to provide sloping rails on one end of a packing case connected by a cross-bar spaced from the case together with a second packing case having a retaining plate or lip secured to one side wall thereof, whereby the second case may be retained on top of the first case providing a desk with an inclined surface.

Other objects and advantages of the invention will be apparent from the accompanying drawings and specification, and the essential features will be set forth in the appended claims.

In the drawings,

Fig. 1 is a perspective view showing three packing cases arranged according to our invention with a portion of one of the cases broken away to more clearly show the construction;

Fig. 2 is a perspective view of the uppermost case of Fig. 1; while

Fig. 3 is a sectional view taken along the line 3—3 of Fig. 1.

We have chosen to illustrate our invention in connection with packing cases used for carrying the equipment for mass chest photofluorography as disclosed in the copending application of Edwin R. Goldfield, Robert J. Stava, and Edgar J. Bastin, Jr., Serial No. 624,172, filed October 24, 1945, although other uses of our invention will occur to those skilled in this art.

The equipment disclosed in the above-mentioned copending application is designed for portability, various parts of which are packed in cases 10, 11 and 12 of the present application. It is desirable, when a large number of persons are being examined rapidly by use of the equipment disclosed in said copending application, that a desk be provided for the operator. The present invention provides a novel manner for constructing such a desk utilizing the packing cases in which the equipment is carried about.

Certain of the cases, such as those shown at 10 and 11 should never be placed upon a support-

ing surface with the end 10a or 11a downwardly. This is because certain equipment is packed in these cases in a predetermined direction and means must be provided on the packing case ends 10a and 11a to insure that these ends are positioned upwardly and not downwardly. A novel structure for this purpose fitting in with the present invention is the provision of parallel inclined skid rails 13 secured to the tops 10a and 11a. These rails are secured by welding or riveting to the metal cases 10 and 11. To this end, the support 13a for the higher end of the skid rail is extended downwardly along the back of the packing case and secured as by welding to the rear wall of the packing case at the point 14. The support at the lower end of the inclined rail 13b is provided with an inturned flange 13c which is secured as by welding to the top of the packing case. Preferably also, an intermediate support 15 is provided generally of Z-shape having one flange 15a secured to the rail 13 and the other flange 15b secured to the top of the associated packing case. A crossbar 16 has its opposite ends welded to the rails 13 so as to provide a unitary structure. Preferably, the rails 13 are part of a strengthening band and skid construction which provides a strong packing case and prevents damage to the same when it is dragged over surfaces. To this end, bands 13a extend downwardly the entire length of the packing case, as indicated at 13d and are then bent at right angles and extend as shown at 13e across the other end of the packing case to the front edge thereof. A hinged door 17 completes the front of the case, but forms no part of the present invention. Preferably, slight humps are formed in the bands 13d and 13e, as indicated at 18, so that if the packing case is dragged across a floor they will protect the bottom and back of the packing case against damage.

The packing case 12 is utilized for the desk top. This case in the present instance is elongated for the purpose of carrying some of the longer portions of the equipment described in the above-mentioned copending application. The case provides parallel side walls 12a and 12b. To the side wall 12a are secured two retaining plates or lips 19 which in the present instance are indicated as spot welded to the wall 12a of the case. The portion 19a of each plate is flat and secured tight against the wall 12a. The portion 19b is bent outwardly from the wall of the packing case by a distance approximately equal to the thickness of the crossbar 16 already described. The top of the packing case 12 is closed by the hinged lid 12c.

Utilizing the above construction, it is very simple to set up a desk after the packing cases have been emptied. The cases 10 and 11 are positioned in spaced alinement as shown in Fig. 1. It will be noticed that the handles 20 are so positioned on the packing cases above the center of gravity that the cases are naturally set down by a workman with the ends 10a and 11a upward. The packing case 12 is then placed across the tops of the cases 10 and 11 with the lips 19b downwardly. By sliding the surface 12a down the inclined skid rails 13, the lips 19b are engaged beneath the crossbars 16, as clearly shown in Fig. 3. The upper side 12b of the packing case now forms an inclined desk surface and a person sitting at the desk will find knee room between the cases 10 and 11.

While we have shown two packing cases supporting the case 12, it should be understood that one packing case might be used, although in our opinion, this would not provide as satisfactory a desk.

What we claim is:

1. In combination, two packing cases, one of said cases having a skid formation on one end thereof providing a surface inclined with respect to the surface of said case end to prevent resting of said end on a supporting surface and to compel the placing of said skid formation upward, a second packing case having generally parallel wide flat sides, and means for securing one of said sides of said second case to said skid formation of said first case, whereby to provide a desk with a sloping top.

2. In combination, a packing case having two parallel skid rails secured to one end thereof, said rails being inclined in the same general direction,

a crossbar connecting said rails, and a desk member having a lip integral therewith, said lip adapted to hook over said crossbar.

3. In combination, a packing case having two parallel skid rails secured to the outside thereof, each rail extending beneath the bottom of the case and then along the back thereof and extending above the top wall of the case, each rail then having a portion extending forwardly and downwardly across the top of the case, whereby said skid rails protect and strengthen three sides of said case and encourage placing said case bottom down, and means connected with said case and rails for anchoring a desk member thereto, whereby a desk member may be secured to said rail portions extending across the top of said case.

4. In combination, a packing case having a pair of parallel skid rails secured to one end thereof, said rails being inclined in the same general direction, a crossbar connecting said pair of rails, a second packing case having generally parallel wide flat sides, and a lip secured to one of said sides and adapted to hook over said crossbar.

5. In combination, two packing cases, each case having a pair of parallel skid rails secured to one end thereof, said rails being inclined in the same general direction, a cross-bar connecting each said pair of rails, a third packing case having generally parallel wide flat sides, and two lips secured in alinement to one of said sides and adapted to hook over the crossbar of said first named cases.

EDWIN R. GOLDFIELD.
RALPH C. SCHIRING.
